LAMP BASE

Guillermo D. Padgett, Youngstown, Ohio

Application September 27, 1956, Serial No. 43,108

Term of patent 3½ years

(Cl. D48—19)

Fig. 1 is a perspective view of a lamp base, showing my new design; and

Fig. 2 is a cross-sectional view taken on line 2—2 of Fig. 1.

I claim:

The ornamental design for a lamp base, as shown.
